Primary Examiner — Joseph Kukella*Assistant Examiner* — Darryl J Dardenne(74) *Attorney, Agent, or Firm* — Kunzler Bean & Adamson(57) **CLAIM**

The ornamental design for a slushie machine, as shown and described.

DESCRIPTION

FIG. 1 is a front perspective view of a slushie machine, showing my new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines in the drawings illustrate the portions of the slushie machine, which form no part of the claimed design.
